UNITED STATES PATENT OFFICE

141,498

DESIGN FOR A GRAIN BIN

Victor C. Norquist and Wilbur B. Larkin, Kansas
City, Mo., assignors to Butler Manufacturing
Company, Kansas City, Mo., a corporation of
Missouri

Application March 5, 1945, Serial No. 118,265

Term of patent 14 years

(Cl. D13—1)

To all whom it may concern:

Be it known that we, Victor C. Norquist and Wilbur B. Larkin, citizens of the United States, residing at Kansas City, in the county of Jackson and State of Missouri, have invented a new, original, and ornamental Design for a Grain Bin, of which the following is a specification, reference being had to the accompanying drawing, forming part thereof, in which,

Fig. 1 is a plan view of a grain bin embodying my design,

Fig. 2 is a side elevational view.

We claim:

The ornamental design for a grain bin, substantially as shown.

VICTOR C. NORQUIST.

WILBUR B. LARKIN.
